UNITED STATES PATENT OFFICE.

CHARLES HEATH AND JOSEPH WILSON, OF MALDEN, MASSACHUSETTS,
ADMINISTRATORS OF JOSEPH B. WILSON, DECEASED.

IMPROVEMENT IN MACHINERY FOR PRESSING BRICK.

Specification forming part of Letters Patent No. 35,650, dated June 17, 1862.

To all whom it may concern:

Be it known that JOSEPH B. WILSON, late a citizen of the United States, and a resident of Malden, in the county of Middlesex and State of Massachusetts, but now deceased, did previous to his death make an invention of certain new and useful Improvements in Machinery for Making or Pressing Bricks, which invention we, CHARLES HEATH and JOSEPH WILSON, administrators of the estate of said JOSEPH B. WILSON, do hereby declare to be fully described in the following specification and represented in the accompanying drawings, of which—

Figure 1 is a top view, Fig. 2 a side elevation, and Fig. 3 a longitudinal and central sectoral section, of a brick-press containing it. Fig. 4 is a side view of its shaft-lever, to be hereinafter described.

The nature of the said invention consists in the combination of a shaft-lever with sectoral toggles or eccentrics and two connecting-rods extending from such lever to a cross head or bar, the whole constituting an arrangement of mechanism for operating the follower of a brick-press, as hereinafter described; also, in the combination of a disengaging spring or its equivalent with the peculiar mechanism for moving the follower into the mold of such a press.

In the drawings, A exhibits the frame of the machine, while B is the brick-mold, which is supported on such frame, and is open in front and rear, so as to be capable of receiving both a platen or follower and a brick-discharger, the former being shown at C and the latter at D.

The platen C is fastened to a slide or carriage, E, while the discharger D simply rests on such carriage and in advance of a post or standard, F, projected upward therefrom. A bearing-screw, a, screws into the said standard. Against the end of the head of this screw the discharger abuts.

In rear of the standard F, and extending across the upper part of the frame A, there is a cross bar or beam, G, which rests on the frame A, and is provided with two buttresses, b b, to serve as bearings for the brick-discharger. At its middle the bar G has a rod, c, projecting backward from it and into and through the

middle of a curved spring, H, the rod at its rear end being provided with a screw, d, on which a nut, e, is screwed in order to connect the spring with the bar G. The said spring at its two ends bears against the posts of the frame A. Furthermore, the bar G has two long rods, I I, applied to it in the same manner as the rod c is applied to the spring H, the rods I I being arranged with respect to the bar G as seen in the drawings. Those ends of the rods I I which are farthest from the bar G are hooked (see Fig. 5, which is a side view of one of them) and catch or hook upon two cranks, d' d', which are formed on a shaft-lever, K, arranged and shaped as shown in Figs. 1, 2, 3, and 4. This lever-bar is provided with journals f f, which extend in opposite directions from it and enter boxes g g, supported by the frame A. At its middle the said shaft-lever is affixed to a sectoral eccentric, L, which gears into another such eccentric, M, applied to the platen or follower C, and having a lever, N, extended from it, as shown in the drawings. The shaft-lever is also furnished with two cams or wipers, O P, one of which, during a depression of the two eccentrics, is intended to act against two projections or arms, R S, (extended from the slide E, as shown in Fig. 3,) and so as to produce such a longitudinal movement of the said slide as will force the discharger C into the mold far enough to produce an expulsion of a brick after it may have been pressed.

In operating with this machine the brick shown at B' should be laid edgewise on a shelf, s, arranged in front of the mold. This having been done, the lever N is to be taken hold of and borne downward, so as to elevate the two eccentrics. While the eccentrics are being so moved the shaft-lever K will be turned in its bearings, and will cause its cranks and their rods I I to operate like toggles and in a manner to draw the cross-bar G a short distance toward the mold, the spring H being at the same time sprung toward the frame. The combined action of the eccentrics, the cranks, and the rods of the rocker lever or shaft will cause the platen to be forced against the brick, so as to crowd it into the mold and firmly condense it therein. This having been done, the

hand-lever is next to be raised, so as to depress the eccentrics, in which case the brick and the platen will be simultaneously expelled from the mold by the retreat or rearward movement of the slide or carriage E. At the moment of greatest pressure of the brick the two bars *t u* of the eccentrics are brought nearly or quite into horizontal positions, in which case the cranks of the lever-shaft will also be turned down horizontally. The spring H, on the motion of the lever N being reversed, will aid in effecting such a movement of the lever and in relieving the brick from the strain upon it. The action of the spring greatly facilitates the upward movement of the lever.

We claim as the invention of the said JOSEPH B. WILSON—

1. The combination of the cranked lever or shaft K and the two connecting-rods I I with

the two sectoral toggles L M and the cross bar G, the whole being applied so as to operate with the follower and the discharger of a brick-press, substantially as specified.

2. The combination of the spring H with the bar G, the rods I I, the cranked shaft K, and the sectoral toggles L M, when employed for operating the follower or platen of a brick-press, as specified.

In testimony whereof we have hereunto set our signatures.

CHARLES HEATH,
JOSEPH WILSON,
Administrators of the estate of the said Joseph B. Wilson.
